UNITED STATES PATENT OFFICE.

ALEXANDER GALLERANI, OF PITTSBURGH, PENNSYLVANIA.

DRYING APPARATUS.

Application filed January 25, 1928. Serial No. 249,241.

This invention relates to apparatus for treating alimentary pastes such as spaghetti, and particularly to drying apparatus therefor.

5 It is among the objects of my invention to provide apparatus of the above designated character which may be adapted to effect a uniform treatment of the material in a minimum amount of time and which shall 10 assure uniform quality irrespective of weather conditions which have had a material influence on apparatus heretofore constructed for the purpose stated.

Another object of the invention is to provide apparatus for treating spaghetti and the like which may be provided with means for regulating atmospheric conditions within the treating chamber for the purpose of controlling the treatment to which the material is subjected.

20 Still another object of the invention is to provide drying and treating apparatus of simple, compact and durable mechanical construction which shall be relatively inexpensive and which shall be capable of treating a relatively large quantity of material in a minimum amount of time whereby a material saving of floor space is effected on account of the greater capacity of the drying 25 apparatus.

Heretofore it has been customary to dry macaroni and spaghetti and similar products by suspending the material fringe-like on suitable racks and subjecting them while 30 so suspended to the action of an air blast or impulses produced by blowers or fans.

In the prior art devices, the fans were disposed with their axes of rotation at right angles to the strands of spaghetti to direct 40 currents of air transversely of the longitudinal axis of the product, thereby setting up a swaying motion to produce a circulation of air around the pending strands of paste. The difficulty encountered by the use of apparatus of this nature are chiefly the inefficient circulation of air on account of the fact that the strands nearest the fan or blower receive the full force of the blast and the material farthest remote from the 45 fan is practically unaffected by the blast, with the result that the finished product varies throughout in quality.

In accordance with the present invention I propose to direct the blasts or air currents 50 in a direction parallel with the longitudinal axis of the strands of spaghetti or macaroni,

and I further provide means for producing a uniform volume of air blast over substantially the entire surface area in which the strands are suspended. I also provide 60 means for directing the blast from both directions of the strands to ensure a uniform volume of circulating air throughout the entire treating chamber.

In the accompanying drawings constituting a part hereof and in which like reference characters designate like parts, Fig. 1 is a front elevational view, partially in section, of the drying apparatus embodying the principles of this invention; and Fig. 2 a top plan view thereof.

Referring to Fig. 1 of the drawing, the structure therein illustrated comprises a chamber constituted by a floor 1, side walls 2 and a top or ceiling 3, the front wall being 75 provided with doors 4 to provide an entrance to the interior of the chamber.

Within the chamber a plurality of vertical supports 5 formed of structural steel members, such as angle irons, are secured to the floor 1 and ceiling 3 and transversely disposed angle irons 6 are secured to the uprights 5 to form racks for receiving sticks or bars 7 upon which the material 8 to be treated, such as spaghetti, is supported in pending strands. The bars 7 carrying the product are arranged transversely of the chamber in the manner illustrated in Fig. 2 and a plurality of spaced apart sections are provided as shown in Fig. 1 to support the 90 loaded bars in superposed relation within the treating chamber. A plurality of propellers 9 are mounted on a shaft 10 which is journaled for rotation centrally of the chamber as illustrated in Fig. 2, the shaft 95 10 being provided with a sprocket gear 11 having a linked connection 12 with a drive gear 13 that is actuated by a motor 14 mounted on a platform 15 supported on the ceiling member 3 of the chamber.

100 As shown in Fig. 1, the propellers are spaced to be disposed between the layers of spaghetti so that each fringe-like layer is subjected to the blast produced by the fan on two sides. Although the propellers are 105 shown at the bottom and between the successive layers of the product and none at the top, it is obvious that the propellers may be mounted on the shaft above the upper layer of product if desired, but on account of the 110 relatively short distance from the top of the upper layer to the ceiling, I have found

that the air forced from the upper fan through the fringes of spaghetti will react from the ceiling sufficiently to subsequently treat the upper row, and the capacity of the upper propeller is further augmented by the propellers disposed between the middle and lower row, so that a propeller above the upper tier of the product may be dispensed with if desired.

10 By disposing the propellers in the manner illustrated in Fig. 1, each individual strand of the product is subjected to a relatively large volume of circulating air which is uniformly distributed between the several strands, and the blast itself produces angular movement of the individual strands appearing as a wave like motion such as wheat growing in a field when acted upon by the wind.

15 In the treatment of products of this kind, it is quite essential to regulate temperature and humidity of the air in the chamber and for this purpose a steam line 17 is provided with suitable valve connections either with- 25 in or without the drying chamber for regulating the flow of steam therethrough. The line is in the form of rectangular coil as shown in Fig. 2 terminating into a connection 18 leading to the source of supply.

20 Within the steam line I provide a plurality of screened openings 19 leading to an air blast which is connected to an air washing device of the type well known in the art. The openings 19 are adapted to be controlled by suitable dampers or shutters to regulate 25 the flow of washed air into the chamber.

25 I further provide a plurality of screened openings 20 around the outer periphery of the chamber although it is immaterial as to the particular location, these openings leading to an exhaust fan or other suitable 40 evacuating device. The exhaust openings may be regulated in the manner of the openings 19 to control the exhaust, it of course being obvious that both the passages 19 and 20 may be closed if desired.

30 In the operation of the apparatus, the product to be treated is supported on bars 7 which in turn are charged into the apparatus by supporting them successively on the transverse angle bars 6 in suitable spaced apart relation as shown in Fig. 2, and layers 35 are built up in the manner as shown in Fig. 1. After the apparatus is fully charged, the motor 14 is energized to rotate the propeller shaft 10 thereby actuating the propellers 9 which set up a forced circulation 45 of air throughout the drying chamber.

The supply of steam is regulated in accordance with the amount of heat required during the different periods of treatment, and the supply of washed air entering through the openings 19 as well as the exhaust air leaving through the perforations or openings 20 is regulated as required. 65

It is obvious from the foregoing description of this invention that apparatus for treating spaghetti and the like, formed in accordance therewith, provides simple and efficient means for treating the product to assure a uniform quality. It is further evident that uniformity of treatment can only be produced by subjecting the individual strings to the action of air blasts as accomplished by the disposition of the propellers 75 in the manner illustrated, whereas if the fans were disposed at the sides of the strands, only the ones adjacent the fans would receive the full effect of the blast.

80 Although one embodiment of the invention has been herein illustrated and described, it will be obvious to those skilled in the art that various modifications may be made in the details of construction without departing from the principles herein set forth. 85

I claim:

1. Apparatus for drying spaghetti and the like which comprises a drying chamber, racks provided in said chamber for sustaining the material in pending strands in superposed layers, a propeller shaft vertically disposed centrally of said chamber, and propellers mounted to rotate with said shaft, said propellers being disposed between successive layers. 95

2. Apparatus for drying spaghetti and the like which comprises a drying chamber, racks provided in said chamber for sustaining the material in pending strands in superposed layers, a propeller shaft vertically disposed centrally of said chamber, propellers mounted to rotate with said shaft, said propellers being disposed between successive layers, and means for maintaining a suitable drying atmosphere in said chamber. 100

3. Apparatus for drying spaghetti and the like which comprises a drying chamber, racks provided in said chamber for sustaining the material in depending strands in superposed layers, and propellers disposed between successive layers and adjacent each end of said strands. 110

In testimony whereof, I have hereunto set my hand.

ALEXANDER GALLERANI.
